UNITED STATES PATENT OFFICE.

CHANDLER R. OTIS, OF SAN FRANCISCO, CALIFORNIA.

VALVE-GRINDING TOOL.

Application filed June 18, 1921. Serial No. 478,464.

To all whom it may concern:

Be it known that I, CHANDLER R. OTIS, a citizen of the United States, residing at San Francisco, in the county of San Francisco and State of California, have invented new and useful Improvements in Valve-Grinding Tools, of which the following is a specification.

This invention relates to improvements in devices for grinding or resurfacing valves and valve seats and resides in the provision of a simple, inexpensive and easily operable device which will simultaneously grind and resurface opposed faces of valves or valve seats.

The primary object of the invention is to provide a device of the character described in which the grinding or resurfacing elements are arranged to automatically adjust themselves to valves and valve seats of various sizes from the smallest type of valve to the larger type regardless of the angularity of the working faces, the said elements being capable of adjustment to any angle from substantially the vertical to substantially the horizontal, or in other words, thru approximately 90° of arc.

Another object of the invention is to provide in a device of the character described novel means for holding the grinding or brasing elements so as to permit adjustment thereof above described, which means is of cheap and simple construction, strong and durable, and capable of being readily assembled and disassembled whereby the renewal of abrasive elements which may become worn may be easily effected.

The invention possesses other advantages and features some of which, with the foregoing will be set forth at length in the following description where I shall outline in full that form of the invention which I have selected for illustration in the drawings accompanying and forming a part of the present specification. In said drawings I have shown one form of the construction of my invention, but it is to be understood that I do not limit myself to such form since the invention as expressed in the 50 claims may be embodied in a plurality of forms.

Referring to the drawings:

Fig. 1 represents an enlarged vertical sectional view of a valve seat such as employed in internal combustion engines, showing the valve in side elevation and the device of this

invention in section and partly in elevation and as it would appear when in use.

Fig. 2 is a bottom plan view of the body or holder for the abrasive elements, 60

Fig. 3 is a bottom plan view of the locking plate for holding the elements in place.

Fig. 4 is an enlarged fragmentary sectional view showing the manner of connecting the abrasive member with the body. 65

Referring to the drawings, 1 designates an annular valve seat, 2 a valve for cooperation with the seat, 3 the valve stem and 4 the spider in which the stem is slidable.

The device of my invention comprises a 70 body generally designated 5, adapted to surround the stem of the valve, and which supports so as to be rotatable thereon and movable into position from substantially near the vertical to substantially near the 75 horizontal, a plurality of small preferably cylindrical abrasive elements or files 6, similar in form to rat-tail files. These files are adapted to lie between the opposed faces of a valve and seat in contact 80 with said faces so that when the valve is rotated said elements will abrade or grind said faces and resurface the latter so as to provide for the desired intimate contact or working fit. 85

The body 5 comprises an annular disc 7 provided with a boss-like or upstanding inner edge 8 and having adjacent said edge thereof a circular series of openings 9. The members 6 are loose and rotatable within 90 said openings and have heads 10 upon their inner ends, which heads engage the inner face of the annular locking plate 11. The disc 5 has a plurality of depending spring clips 12 around its outer edge, which clips 95 hold the locking plate in close engagement with the under side of the disc. The inner edge of the locking plate is turned upwardly, slightly, and spaced from the upturned portion 8 of the disc 7 so as to provide sufficient space to accommodate the heads 10 of the files 6 and permit free movement of said files but so as to hold the files in place as shown in Figs. 1 and 2. By use of the spring clips the locking plate 100 105 may be quickly and easily removed or fitted into place.

A helical expansion spring 13 is secured at one end in eyes 14 formed in the under side of the locking plate 11. The eyes are 110 formed by striking material downwardly as shown in Figs. 1 and 3. The other end of

the spring is adapted to engage the spider 4 so as to hold the body 5 and files 6 in position to operate upon the valve in its seat.

To use the tool or device of my invention, 5 the valve is removed and the stem 3 is inserted back in place so as to extend thru the body 5 and spring 13 as shown in Fig. 1, whereupon the files or abrasive members 6 will be disposed between the opposed faces 10 of the valve and its seat. Upon turning the valve in the ordinary manner as is customary in grinding or resurfacing, by use of a tool, not shown, the cylindrical abrasive members will be rotated and in so doing 15 will abrade the opposed faces and resurface them so that they will be ground for close and proper working contact. The small circular abrasive elements provide for efficient and expeditious grinding action 20 much more so than is the case with the ordinary grinding compounds commonly used for fitting, grinding and dressing valves and seats. In the event that one or more of the files becomes worn and replacement thereof 25 is necessary, this can be quickly and easily accomplished by prying out the spring clip 12 portion so as to allow for the removal of the locking plate 11. When the plate 11 is removed the pin-like files 6 which are to be 30 renewed can be easily removed and the new ones inserted. One of the most essential features of this invention is the provision of a body such as the one 5, which holds a plurality of abrasive members so that the 35 latter are rotatable and movable thru substantially 90° of arc, whereby the device is applicable to valves of various sizes and having various angles as to their opposed faces.

40 The substantially flat body with no projection or obstruction around the outer edge thereof, provides for adjustment of the abrasive members so that the device may be used with valves of the larger sizes as 45 well as with very small valves and their seats. The body is for the most part below the plane of the lower ends of the members 6.

I claim:

50 1. A valve grinding device comprising a body portion thru which the stem of a valve to be ground is inserted, a plurality of abrasive members supported and arranged on the body so as to be rotatable between and 55 in engagement with the opposed faces of the valve and its seat and to be movable thru

approximately 90° of arc from substantially the vertical to substantially the horizontal, spring clips depending from the body and a locking plate removably held in place by 60 the clips to hold the abrasive members on the body.

2. A valve grinding device comprising a body member and a plurality of cylindrical abrasive elements mounted for rotation on 65 said body and arranged in a circular series thereon, said members being attached at the inner ends to the body and free at their other ends.

3. A valve grinding device comprising a 70 body having a circular series of openings therein, a plurality of cylindrical abrasive members mounted loosely and for rotation in said openings, heads on the inner ends of said members of larger diameter than the 75 openings, spring clips depending from said body, a locking plate removably held against the under side of the body in engagement with said heads by said spring clips.

4. A valve grinding tool comprising a body 80 member adapted to surround a valve stem, an annular member supported upon said member and having a plurality of radial openings therethru and pin-like projecting members revolvable in said openings. 85

5. A valve grinding tool comprising a member adapted to be mounted upon a valve stem, an annular member supported by said member and having a plurality of radial openings therein, pinlike projecting members 90 revolvable in said openings and heads on the inner ends of said members.

6. A valve grinding tool comprising a member adapted to surround a valve stem, an annular member supported by said member 95 and having a plurality of radial openings therein, pinlike projecting members revolvable in said openings, heads on the inner ends of said projecting members and an annular member on the first named member 100 spaced circumferentially from a part of the annular member having openings therein, said heads being disposed between said annular members.

7. A valve tool comprising a body member, a plurality of members adjustably mounted upon and projecting outwardly from the body member and arranged to engage between a valve and its seat, said projecting members being free at their outer 110 ends.

CHANDLER R. OTIS.
